UNITED STATES PATENT OFFICE.

STROWBRIDGE B. SEATON, OF CHICAGO, ILLINOIS, ASSIGNOR TO INTERNATIONAL TAG CO., OF CHICAGO, ILLINOIS, A CORPORATION OF NEW JERSEY.

SHIPPING-TAG.

1,373,916.

Specification of Letters Patent. Patented Apr. 5, 1921.

Application filed March 17, 1919. Serial No. 283,175.

To all whom it may concern:

Be it known that I, STROWBRIDGE B. SEATON, citizen of the United States, residing at Chicago, in the county of Cook and State of Illinois, have invented a certain new and useful Improvement in Shipping-Tags, of which the following is a full, clear, concise, and exact description, reference being had to the accompanying drawings, forming a part 10 of this specification.

The invention relates to shipping tags, and has among its various objects the production of a tag composed of separable portions; one portion, a reinforced tag of ordinary style, to bear the name and address of both shipper and consignee; the other portion, a reinforced stub tag auxiliary thereto, for the purpose of bearing such indicia as will serve to identify the shipment and 20 either the shipper or consignee or both in any event of the larger tag being mutilated or torn from the package.

It is a further object to provide each of the portions of the tag with information regarding the shipper together with a means 25 of identification of the article to which the tag is attached so that the carrier may refer thereto, in seeking information from the shipper should the portion bearing the consignee's name and address become removed, defaced or otherwise rendered useless.

The invention has an added object, an arrangement whereby one portion of the tag having certain information is protected 35 against being defaced or otherwise eliminated by the elements or other causes.

It is one of the objects of the invention to produce a tag having these qualities, which is extremely simple in construction, yet efficient in operation, and which eliminates the necessity of providing a special reinforcing portion which is usually pasted or glued to the tag which materially adds to the expense of manufacture without producing a corresponding increase in efficiency.

The invention will be explained in detail and more readily understood when read in conjunction with the accompanying drawings in which,

50 Figure 1 is a view of the tag showing the position the parts will assume when applied for use;

Fig. 2 is a view of the card shown in Fig. 1 showing its condition prior to being 55 formed as in Fig. 1;

Fig. 3 is a perspective view of one end of the card formed as illustrated in Fig. 1; and

Fig. 4 is a modified form of construction.

In the embodiment of the invention 60 shown in the drawings the same contemplates the use of a tag composed of integral portions 10 and 11 connected together by the perforated or weakened portion 12. The portion 10 may be provided with the name 65 and address of the shipper together with a space 13 provided for the insertion of an invoice or other number. This portion of the tag also contains spaces 14 for the name and address of the consignee.

70 The end of this portion of the tag nearest the perforated portion 12 is provided with an eyelet 15 which is preferably of the reinforced type and prevents this portion of the tag from becoming separated from the wire or cord 16 whereby the tag is secured to the article, when any ordinary force or pulling strain is exerted thereon.

75 The portion 11 is connected to the portion 10 through the medium of the perforated part 12 which permits this portion to be folded upon the portion 10 as illustrated in Fig. 1 and also provides the means whereby these portions 10 and 11 may be severed from each other when a strain sufficient to accomplish this is exerted upon a portion such as the part 10.

80 The portion 11 is also provided with an eyelet 16 which is also of the reinforced type. When the portion 11 is folded over 85 the part 10 these eyelets 15 and 16 register with each other and permit the passage of a wire or cord 16 therethrough, whereby these parts forming the tag may be secured to the goods to be shipped. In the arrangement shown in Fig. 1 the outer face of this 90 stub 11 is provided with the name of the sender together with the space 17 for the insertion of a number or other indicia that will identify the shipment. Thus should the portions 10 and 11 become separated and the 95 portion such as 10 lost, the carrier may by communicating with the firm whose name appears upon the stub 11 and by referring to the number on this stub when communicating readily receive the desired information so as to forward the article to its destination.

100 While this portion 11 is provided with the name of the shipper it is evident that the name of the consignee may be ap- 105 110

plied upon this portion instead of or in addition thereto, thus providing a double insurance of the package, parcel or article to which the card is attached, reaching its destination should the portion 10 become destroyed or lost.

In the embodiment of the invention shown in Fig. 4, the stub end 11 corresponds in every respect to that shown in Figs. 1 and 2 only differing therefrom in that the printed or written matter thereon is provided on the inner instead of the outer face thereof when the stub is folded against the portion 10. This arrangement protects any information which may be contained thereon and prevents the same from becoming soiled or mutilated or erased.

In each of the structures illustrated the corners of the tag at the folded portion of the card are cut away to form a bevel edge 17. This reduces the possibility of wear, by their contact with other objects at these points.

When the portions forming the tag are arranged to be secured to an article for shipment, the portion 11 is folded upon the part 10 at the perforated or weakened portion 12, and a wire or cord is then passed through both of the reinforced eyelets 15 and 16 and fastened to the goods to be shipped.

This produces a tag which corresponds to the usual shipping tag in respect to the features of appearance to strength and durability and which cannot be removed by any ordinary cause from the goods to which it is attached, and in addition thereto has the added feature of permitting one portion thereof to be severed from the other when a strain which is in excess of the resisting power of the tag is exerted thereon.

This separation of one part of the tag from the other is permitted by the construction which connects the two cards together, which is the weakest portion of the card, it being weaker than either of those portions through which the attaching wire or cord is passed. Thus should the tag proper or portion 10 be subjected to a strain greater than its resisting qualities, it will separate from the stub or portion 11 as well as from the package, leaving the stub portion 11, from which the carrier can obtain the necessary information to identify the consignor or consignee, or both, depending upon the matter printed thereon. When an undue pulling strain is exerted upon the main portion 10 of the tag, the effect will be to cause the fastening cord or wire 16^a to cut through the eyelet 15 or cause such main portion to be torn away from said eyelet, and such pulling strain will, at the same time effect a separation of the two members of the tag along the weakened or perforated line 12. Thus while the main tag member 10 may be wholly separated from the package to which it has

been addressed, the auxiliary or stub member 11 will remain connected through the attaching device 16^a with such package, and, as hereinbefore stated, the information given by the printing or other marking thereon will enable the person in charge of the package to locate either the consignor or consignee or both.

It is evident that both portions of the card may be of equal length instead of different lengths as illustrated, also that one card may contain the name of the shipper and consignee together with an identifying shipment number and the other only the name of the shipper together with a corresponding number and other different combinations, all of which I contemplate as coming within the scope of the invention as expressed in the appended claims.

Having thus shown and described my invention, what I claim and desire to cover by Letters Patent is:

1. A shipping tag comprising integral separable portions, each having means adjacent one end only of the tag for the reception of means whereby both portions of said tag may be attached to an article, said tag being adapted to permit one portion thereof to be released from the other portion when a strain sufficient to release it from the attaching means is exerted upon it.

2. A shipping tag comprising two separable portions, a weakened portion connecting said portions together, reinforced apertures provided in each of the separable portions for the reception of a means for securing the tags to an article, one of the separable portions being folded upon the other at the weakened portion, said reinforced apertures registering with each other when said portions are folded, said weakened portion permitting the separation of one portion from the other when a strain sufficient to release it from said means is exerted thereon.

3. A shipping tag comprising separable portions, a weakened portion connecting said portions together, each of the separable portions having means provided for the reception of a member whereby both portions may be attached to an article, one of said first mentioned portions being folded upon the other at the weakened portion, said weakened portion permitting the separation of one of the separable portions from the other when a strain sufficient to release it from said member is exerted thereon.

4. A shipping tag comprising separably connected portions, each portion being adapted to receive a member whereby both portions may be attached to an article, said portions being connected together, one portion of the tag being detachable from the other portion at the connection when a strain sufficient to release it from said member is

- exerted thereon, and each portion of the tag having means of identification provided thereon.
5. A shipping tag comprising integral portions connected together by a weakened portion, one of said sections being folded upon the other, both of said portions having means provided for the reception of a member whereby both portions may be attached to an article, said weakened portion permitting the separation of one portion from the other when a strain sufficient to release it from said member is exerted thereon.
6. A shipping tag composed of two separable portions, each portion having means provided for the reception of a member whereby both portions may be attached to an article, means connecting both portions together whereby one portion of the tag may be detached from the other portion when a strain sufficient to release it from said member is exerted thereon, one of said portions forming the tag being folded upon the other, means of identification provided upon each portion, and the last mentioned means of one portion being provided on that portion thereof which faces the other portion when said portions are in folded relation to each other.
7. A tag comprising two members formed from a single piece of material folded transversely along a weakened line, each of said members being provided with an opening adjacent to said line of fold to receive means for attaching both members to an article, whereby a pulling strain upon one member sufficient to tear it from such fastening means will also detach it from said other member along said weakened line without removing said other member from such fastening means.
8. A tag comprising two members formed from a single piece of material folded transversely along a weakened line, said members being provided with aligned openings adjacent to said line of fold for the passage therethrough of a single fastening device, whereby a pulling strain upon one member sufficient to tear it from such fastening device will also detach it from said other member along said weakened line without removing it from said fastening device.
9. A shipping tag comprising two portions separably connected together, means for attaching both portions to an article, one of said portions being separable from the other portion at the connection when a strain sufficient to release it from the attaching member is exerted thereon.
10. A shipping tag comprising two portions separably connected together, one portion being larger than the other, a fastening member for securing both portions to an article, the smaller portion being detachable from the larger portion at the connection when a strain upon such larger portion that is sufficient to release it from the attaching member is exerted on such larger portion.
11. A shipping tag comprising two portions separably connected together, one of which is smaller than the other, a fastening member attached to each portion for securing both of said portions to an article, one of said portions being separable from the other portion at the connection when a strain sufficient to release it from the fastening member is exerted upon it, and means of identification provided upon the smaller portion of the tag.
12. A shipping tag comprising main and auxiliary portions, a reinforced aperture provided in each portion, an attaching member passing through both apertures for securing both portions to an article, the auxiliary and main portions being detachably connected together and said attaching member coöperating with the auxiliary portion to enable the separation thereof from the main portion, the fastening member retaining said auxiliary portion attached to the article after such separation.
13. A shipping tag comprising main and auxiliary portions, each having a reinforced aperture provided therein, an attaching member passing through both apertures for securing both portions to an article, said portions being separable between the reinforced apertures of the two portions, said attaching member coöperating with the auxiliary portion to enable the separation thereof from the main portion when a pulling strain is exerted upon said main portion, the fastening member retaining said auxiliary portion attached to the article after such separation.

In witness whereof, I hereunto subscribe my name this 3rd day of March A. D., 1919.

STROWBRIDGE B. SEATON.
